Primary Examiner — Cynthia Underwood(74) *Attorney, Agent, or Firm* — Greenblum & Bernstein, P.L.C.(57) **CLAIM**

I claim the ornamental design for a can-shaped container, as shown and described.

DESCRIPTION

FIG. 1 shows a top side perspective view a can-shaped container;

FIG. 2 shows a top side view of FIG. 1; and,

FIG. 3 shows a side view of FIG. 1 but with the container oriented horizontally.

Any surfaces of the design not shown, including interior surfaces and any surfaces shown in broken lines, form no part of the claimed invention.

1 Claim, 3 Drawing Sheets***FIG. 1***

FIG. 2

FIG. 3
